UNITED STATES PATENT OFFICE.

BIRNEY C. BATCHELLER, OF NEW YORK, N. Y.

TIMING MECHANISM.

1,087,631.

Specification of Letters Patent.

Patented Feb. 17, 1914.

Original application filed July 23, 1909, Serial No. 509,144. Divided and this application filed February 26, 1912. Serial No. 679,969.

To all whom it may concern:

Be it known that I, BIRNEY C. BATCHELLER, a citizen of the United States of America, residing in New York, in the borough of Brooklyn and State of New York, have invented a certain new and useful Improvement in Timing Mechanism, of which the following is a true and exact description, reference being had to the accompanying drawings, which form a part thereof.

My present invention relates to timing devices particularly adapted for use in pneumatic despatch tube systems.

The object of the invention is to provide a simple, effective and reliable timing mechanism peculiarly adapted for, but not necessarily limited to, use in controlling a motor employed for supplying air to the transit tubing of a pneumatic despatch tube system, in such manner as to insure the operation of the motor for a definite time interval after the insertion of a carrier into the transit tubing.

The various features of novelty which characterize my invention are pointed out with particularity in the claims annexed to and forming a part of this specification. For a better understanding of the invention however and the advantages possessed by it, reference should be had to the accompanying drawings and description in which I have illustrated and described forms in which the invention may be embodied.

Of the drawings: Figure 1 is a diagram illustrating the use of one form of my invention in a transit tube system. Fig. 2 is an elevation of a contact mechanism employed. Fig. 2^A is a partially inverted sectional plan taken on the line 2^A—2^A of Fig. 2. Fig. 3 is a plan of the timing mechanism proper of Fig. 1. Fig. 4 is a section on the line 4—4 of Fig. 3 and Figs. 5 and 6 are diagrams, each illustrating a different modification of the arrangement shown in Fig. 1.

Referring first to the arrangement shown in Figs. 1 to 4 inclusive, A' and A² represent two of the generally similar sections of the transit tubing of a pneumatic despatch tube system. Each of the sections A' and A² has carrier admission and discharge provisions at its opposite ends. The admission provisions A⁴ for both sections and the discharge provisions A⁵ of section A' only are shown in the drawings. In the system shown the carriers are transmitted by com-

pressed air supplied to the section A' from the air compressor or pump B through the pipe A. From section A', air for moving the carriers in section A² is passed to the latter section through the pipe A³. It will of course be understood that the pneumatic despatch tube system supplied with air by the pump B may include more sections of transit tubing than the tube sections A' and A² shown.

The pump B is driven by an electric motor C, receiving current under conditions hereinafter explained from the supply conductors 1 and 2. The supply of current to the motor C is controlled to properly start and stop the motor by a rheostat controller D, controlled in turn by a switch E, the opening and closing of which is controlled by the novel timing device G which I will now describe.

The device G includes a casing G³ having a removable top G⁴, and inclosing gearing connecting the electric motor H with a clutch mechanism hereinafter described. In the form shown in Fig. 1 the motor H is in constant rotation. The motor H is mounted on a bracket G⁵ projecting from the front of the casing G³, and shown in Fig. 4. The shaft H' of the motor projects into the casing G³ and carries a worm H² meshing with and driving a gear G⁶ secured to a shaft G⁷. The shaft G⁷ carries a worm gear G⁸ meshing with and driving a gear I² carried by a shaft I' which extends parallel to the motor shaft H' and projects through, and is journaled in the front wall of the casing G³. Without the casing G³, the shaft I' carries a disk I³, having an annular groove receiving an annular bearing member I⁴. Beyond the disk I³, on an extension I⁵ of the shaft I' are loosely mounted a member J having a disk like body portion, a disk like armature K, and a spring pressed follower sleeve I⁶. The follower sleeve I⁶ is at all times pressed against the armature K by a spring I⁷, the outer end of which bears against nuts I⁸ adjustably threaded on the shaft extension I⁵.

To brackets G⁹ and G¹⁰, projecting from the casing G³ is secured the shell K' of an ironclad electromagnet, the shell K' being provided with an annular cavity K² surrounding the shaft extension I⁵. Within the cavity K² is placed a magnet winding K³, the terminals of which are secured to 110

binding posts K^4 projecting from the front side of the shell K' .

When the magnet K^3 is energized, the armature K is drawn toward it, overcoming the spring I^7 , and the member J is then free to move into the position shown in Fig. 4, which it does under the action of a weight J^2 sliding in the casing J^6 . The weight J^2 is connected to the member J by a flexible member or cord J^5 which partially encircles the disk like body of the member J , the latter being provided with a groove J^4 in which the cord J^5 is received. An arm J' of the member J engages the bracket G^9 to prevent movement of the member J under the influence of the weight J^2 beyond the position shown in Fig. 4. When the magnet winding K^3 is deenergized, the spring I^7 through the follower I^6 and armature K , presses the member J against the bearing I^4 of the disk I^3 with such force that the member J is rotated with and by the shaft I' in the direction of the arrow applied to Fig. 1 until the rotation of the member J in this direction is stopped in the manner in which I will now describe.

The arm J' of the member J is provided with a lug J^{10} which when the member J' is moved into the dotted line position shown in Fig. 2, engages a bridge piece G^{11} which is flexibly supported by bowed resilient conducting strips G^{12} secured to a contact G' mounted on an insulating support G^{13} secured to the front of the casing G^3 by the adjustable arm G^{14} . The support G^{13} also has secured to it a contact G^2 , and when the arm J' engages the bridge piece G^{11} , it forces the latter to the left from the position shown in Fig. 2 until the contact strips G^{12} electrically connect the contacts G' and G^2 , and further movement to the left of the bridge piece G^{11} is prevented. As is clearly shown by Figs. 2 and 2^A the contact G^2 is rabbeted and has one surface G^{20} against which the end of the contact strip G^{12} , which is free, contacts, and has another surface G^{21} against which the contact strip G^{12} secured to the bridge piece G^{11} contacts when the circuit is fully closed. The surface G^{20} and the contact strip which engages it serve in a well known manner to prevent arcing from taking place between the surface G^{21} and the other contact. The frictional coupling between the disk I^3 and the member J then yields to permit the member J to remain stationary until, the winding K^3 is again energized, without interfering with the rotation of the shaft I' which is continuously driven in the same direction by the constantly running motor H .

At each of the transmitting stations A^4 , a switch mechanism L is provided, which serves to connect a corresponding pair of branch conductors 17 and 18 whenever a carrier is inserted in the transit tubing at

that station for transmission. The branch conductors 17 and 18 are connected to conductors 19 and 20, respectively. The conductor 19 is connected to the supply conductor 2 through the resistance 21, and the conductor 20 is connected to one of the terminals K^4 of the winding K^3 . The other terminal of the winding K^3 is connected to supply conductor 1 by a conductor 22. The terminals of the motor H are connected to the supply conductors 1 and 2 by conductors 14 and 15, the latter conductor including a suitable resistance 16.

From the foregoing it will be understood that whenever a carrier is inserted at any station A^4 , the winding K^3 is energized and the armature K is moved toward the winding to release the member J from its frictional engagement with the disk I^3 and that the member J is then returned to the position shown in Fig. 4, regardless of whether the member J had been previously moved fully into or only part way toward the position shown in dotted lines Fig. 2. The speed of the motor H is so chosen and the gearing between it and the shaft I' is so arranged that the movement of the member J from the position shown in full lines in Fig. 4 to the position shown in dotted lines in Fig. 2 requires a time interval during which the pump is in operation, amply sufficient to move the carrier last inserted to the end of its journey. Where the invention is used, as in the transmission of mail, in what are known as large tube systems, this interval may be about four minutes. It will of course be apparent that if a second carrier is inserted while a previously inserted carrier is in transit, the member J will be returned, from the intermediate position into which it has been moved, back to the position shown in Fig. 4. In consequence, when carriers are inserted with sufficient frequency, the member J may be prevented during long intervals from moving into the dotted line position of Fig. 2, but whenever the period following the insertion of the last carrier is sufficient to permit member J to be moved from the full line position of Fig. 4 into or more accurately slightly beyond the dotted line position of Fig. 2, the contacts G' and G^2 are then connected and the motor C is stopped, thus preventing useless expenditure of energy in operating the pump B when there is no need for such operation.

I will not describe in detail the particular mechanism disclosed by which the timing device serves to stop and start the motor C , but I wish it to be understood that any suitable kind of motor starting and stopping mechanism, of which many kinds are now known, may be used, and that the exact character of the motor starting and stopping mechanism proper, diagrammatically illus-

trated in Fig. 1 forms no feature of the present invention.

The switch E is carried by the armature or core E' of a solenoid magnet, the winding E² of which has one terminal connected to the supply conductor 1 by a conductor 10. The other terminal is connected to the contact G' by a conductor 11. The contact G² is connected by a conductor 12, including a resistance 13, to the supply conductor 2. When the contacts G' and G² are connected together by the conducting strips or switch members G¹², winding E² is energized and switch E is opened and when the contacts G' and G² are disconnected, winding E² is deenergized and the switch E drops into the closed position. Attention is called to the fact that while the contacts G' and G² are closed by the slow movement of the member J, produced by the rotation of the shaft I', the contacts G' and G² are disconnected by the rapid movement of the member J, caused by the weight J². This rapid movement of the switch connecting contacts G' and G², has an obvious advantage in preventing injurious sparking between the contact G² and the conducting strips G¹². One of the two terminals connected by the switch E when the magnet E² is deenergized, is connected by conductor 8, including a resistance 9, to the supply conductor 2. The other terminal of the switch E is connected by conductor 7 to one terminal of the solenoid magnet coil D⁴ of the automatic rheostatic controller D. The second terminal of coil D⁴ is connected by a conductor 6 to the supply conductor 1. The core or armature D⁵ of the coil D⁴ is connected by a link D⁶ to the switch arm D'. The latter travels over a series of contacts D⁸ connected by resistance D². One terminal of the motor C is connected by conductor 3 to supply conductor 1, and the other terminal of the motor is connected by a conductor 4 to the switch arm D'. The upper contact D⁸ is connected by a conductor 5 to the supply conductor 2. When the switch E connects the conductors 7 and 8 and the winding D⁴ is energized, and the switch arm D' is first moved into engagement with the lowermost contact D⁸, thus connecting the motor to the supply conductors 1 and 2 through all of the resistance D², and then the resistances D² are cut out, one after another, as the switch arm D' continues to move upward. A dash pot D⁷, or like retarding device may be connected to the switch arm D' to regulate the speed at which the resistances D² are cut out.

In the arrangement shown in Figs. 1 to 4 inclusive the driving shaft I' of the timing mechanism is constantly rotated by the motor H but this is not necessary in all cases and in Fig. 5 I have shown in diagram a portion of a system identical with that of

Fig. 1 except that the conductor 15 and resistance 16 are replaced by a conductor 151 connected to one of the terminals controlled by the switch E. In this case the circuit of the motor H includes conductors 8, 151 and 14 and is closed only when the magnet E is deenergized and in consequence the motor H does not run except when it is desired that the motor C should also rotate.

In Fig. 6 I have a system like that of Fig. 1 except that the auxiliary small motor H and circuit connections therefor are dispensed with and the shaft I' is driven by the motor C through suitable connections which, as shown, comprise the shaft M and the meshing gears C² and M' and M² and I⁹, gear C² being secured to shaft C' of motor C, gears M' and M² to shaft M, and gear I⁹ to shaft I'. In Fig. 6 the disk K and the electromagnet and the disk I⁸ are transposed with respect to the position occupied by these elements relative to the disk J, as shown in Figs. 3 and 4. Where the rotation of the shaft I' is not continuous but intermittent as in Figs. 5 and 6, the arrangement must of course, be such that the member J will not start to reverse its direction of rotation and thereby permit the breaking of the connection between contacts G' and G² when the motor driving shaft I' is stopped. In the arrangement shown in Figs. 1 to 4 inclusive, the character of the gearing between the shaft I' and the motor H and particularly the worm and wheel connection between the shaft I' and G⁷ is such that while the motor H can rotate shaft I' the latter cannot rotate the motor. In Fig. 6 the friction of the connected mechanisms including the motor C and the air pump B prevents the backward rotation of the member J when the motor C is open circuited.

With the arrangements shown in Figs. 5 and 6 I avoid any waste of current used in driving the timing device when the motor C is not required to operate and with the arrangement of Fig. 6 I avoid the necessity for any auxiliary motor. I may say however that in general I prefer the arrangement of Fig. 1 on account of the certainty and reliability of operation obtained thereby.

It will be apparent to those skilled in the art that the timing mechanism disclosed is compact, durable, effective and reliable, and well adapted for the particular purpose for which it is designed. By operating the timing device electrically I avoid the necessity of providing any tank or tanks for the storage of fluid under pressure such as would be necessary if a fluid pressure timing device were employed and have the advantage of a constant and reliable source of power. It will be apparent also to those skilled in the art that this timing mechanism is capable of use, either in whole or in part, in other relations than the one shown.

The transit system disclosed herein possess patentable features which are not claimed herein, but are claimed in my prior application, Serial Number 509,144, filed 5 July 23rd, 1909 of which the present case is a division.

Having now described my invention, what I claim as new and desire to secure by Letters Patent is,

10 1. A timing mechanism comprising rotatable driving and actuating members having coöperating surfaces adapted to be held in frictional engagement whereby the rotation of said driving member tends to rotate 15 said actuating member, a spring for yieldably holding said surfaces in frictional engagement, a stop engaged by the actuating member after a predetermined movement thereof away from an initial position and 20 preventing further movement of said member away from said initial position, electro-magnetic means for overcoming the action of the spring and separating said surfaces, and means for returning said actuating member 25 to said initial position when said surfaces are separated.

2. A timing mechanism comprising rotatable driving and actuating members having coöperating surfaces adapted to be held in 30 frictional engagement whereby the rotation of said driving member tends to rotate said actuating member, means normally acting to hold said surfaces in frictional engagement, a stop engaged by the actuating member after a predetermined movement thereof away from an initial position and preventing 35 further movement of said member away from said initial position, intermittently acting means for overcoming the action of the first mentioned means and separating said surfaces, and means for returning said actuating member to said initial position when said surfaces are separated.

3. A timing mechanism comprising in 45 combination, an electric motor, a casing on which said motor is externally supported and into which the shaft of the motor projects, a second shaft projecting through the casing and provided externally thereof with 50 a friction disk, gearing within the casing connecting said second shaft with the motor shaft, a member loosely journaled exteriorly of the casing coaxially with said second

shaft and adapted to engage said friction disk, a spring pressed armature for holding 55 said member against said disk, a magnet supported by the casing and adapted, when energized, to attract said armature and free the member from the disk, a stop limiting the movements of the member with the disk, 60 and a weight for returning the member to an initial position when the magnet is energized.

4. A timing mechanism comprising a motor and actuating member having co- 65 operating surfaces adapted to be held in frictional engagement whereby the rotation of said motor tends to rotate said actuating member, means normally acting to yieldably hold said surfaces in frictional engagement, 70 a stop engaged by the actuating member after a predetermined movement thereof away from an initial position and preventing further movement of said member away from said initial position, means adapted to 75 be intermittently actuated for overcoming the action of the first mentioned means and separating said contact surfaces, and means for returning said actuating member to said initial position when said surfaces are separated.

5. A timing mechanism comprising in combination, a motor, an actuating member, means normally acting to yieldably couple said motor and member together whereby 85 said motor may move said member away from an initial position, a stop engaged by the said member after a predetermined movement of said member away from an initial position and preventing further 90 movement of said actuating member away from said initial position, means adapted to be intermittently actuated for rendering the first mentioned means inoperative, means for returning the actuating member to said 95 initial position when said first mentioned means are rendered inoperative and controlling mechanism for said motor actuated by said actuating member to stop said motor with said stop and to start said motor when said member returns to said initial position.

BIRNEY C. BATCHELLER.
